ABSTRACT OF THE DISCLOSURE

Horizontally oriented hydrocyclones disposed in superimposed layers are arranged to discharge light fractions into a common compartment and heavy fractions into another common compartment. A third compartment is arranged common to all feed inlets. Conduits and regulating devices maintain the operational levels in the compartments above the heavy fraction outlets in the uppermost layer.

The present invention relates to a method of separating a suspension into a light fraction and a heavy fraction in hydrocyclone separators and, more particularly, in a hydrocyclone separator unit or assemblage including a plurality of hydrocyclone separators, each of which comprises an elongated chamber of circular cross section having at one end a first outlet for the discharge of the light fraction and at the other end a second outlet for the discharge of the heavy fraction. The invention also relates to the structure of such hydrocyclone separators for effecting separation of the suspension in accordance with the method of the invention.

The separation efficiency of hydrocyclone separators generally depends, to a large extent, upon the dimensions and, more particularly, upon the effective flow areas of the discharge outlets for the light fraction commonly referred to as "accepts" and the heavy fraction commonly referred to as "rejects."

It is a general rule that the smaller the discharge outlet is for the rejects, the smaller will be the proportion of the accepts which are discharged through this outlet and thus lost. In respect of the rejects, the condition is the opposite to a certain extent, the smaller the discharge outlet is for the rejects, the larger will be the proportion of the rejects which are discharged through the discharge outlet for the accepts. In other words, the separation efficiency of the separator is correspondingly lowered. Accordingly, the problem is to select for the discharge outlet for the rejects an effective flow area which is dimensioned so that an optimal overall efficiency is attained as to both, the losses of accepts, such as fibers and the separation efficiency. Generally stated, particularly for multiple hydrocyclone installations in which the individual separators are usually quite small, the conditions for the aforesaid overall optimal efficiency involve that, especially in view of the relatively low back pressure in the heavy fraction receptacle owing to the free outflow of the heavy fraction, the discharge outlet for the heavy fraction, or rejects, has to be provided with an effective flow area which is so small that there is a pronounced danger of clogging in this outlet. Such clogging, of course, completely stops the separating operation, or at least reduces the capacity of the separator to a substantial extent.

When separating suspensions in hydrocyclones and especially fiber suspensions, it has been considered practically axiomatic to provide a free outflow of the heavy fraction or rejects from the hydrocyclones because it was deemed to be necessary to be able to follow the separation operation and immediately to take any measures possibly re-

2

quired. This request remained also when hydrocyclone separator units became available, the separators of which were enclosed in a common housing and it was therefore necessary to provide such units with special automatic rinsing or flushing means for the reject outlet nozzles to prevent clogging. The equipment necessary to effect such automatic rinsing or flushing is, however, rather complicated and expensive and it has been found that the use of anticlogging equipment introduces difficult problems, especially in the operation of multicyclone installations as for instance when an outlet is clogged immediately after a flushing has taken place and hence will be clogged during the whole period before next flushing.

In some fields of application, such as an installation in which hydrocyclone separators are used ahead of a paper-making machine, the use of special rinsing or flushing equipment is not possible at all and hence also not the use of separators which satisfy the aforementioned optimal operational conditions since the rinsing or flushing, which is carried out periodically at selected time intervals, causes fluctuations in the flow of accepts discharged from the hydrocyclone separator. In connection with the making of paper, no fluctuations at all in the flow of the suspension can be tolerated.

According to the invention, the above stated disadvantages are avoided primarily by carrying out the separation in hydrocyclone separators, the second or reject outlet of which is greater than the inlet and of such a magnitude that under normal conditions no clogging of the reject outlet is possible and by maintaining in a receptacle for the heavy fraction or rejects an operational level which is above the said second outlet, a back pressure being also maintained at the outside of said second outlet. Under special conditions this may entail that the outlet for the rejects has to be so great that too high a back pressure will be required and that there is a danger that heavy fraction or rejects will be sucked back into the separator thereby adversely affecting the separation efficiency. To prevent any such disadvantages, the inlet to the separator may comprise several ducts whereby the outlet for the rejects need only to be made greater than any of said ducts. The danger of said outlet being clogged will thereby be considerably reduced due to the fact that also smaller particles which might cause a clogging will be caught by some of the inlet ducts.

As a result of the invention the danger of clogging of the heavy fraction outlets of the hydrocyclone separators is practically wholly eliminated. Hence the aforementioned special rinsing or flushing equipment is ordinarily not required. As it is evident from the previous explanation, separators according to the invention which, for all practical purposes are not subject to clogging, can be readily used also in the paper making industry since rinsing operations are omitted and hence cannot cause fluctuations in the flow of the suspension discharged from the separator.

The present invention is of special importance for hydrocyclone separator units including a plurality of stacked hydrocyclone separators disposed in several layers and with their geometric axes in an at least substantially horizontal orientation. In hydrocyclone separator units of the kind referred to it is possible to maintain when the separator is in operation, an operational level of the light fraction and an operational level of the heavy fraction which are of at least substantially the same height and above said second outlet of the hydrocyclone separators in the uppermost one of said operational layers. By maintaining such levels in receptacles for the light fraction and the heavy fraction, respectively, the ratio of outflow of the light fraction and the heavy fraction as well as the separation efficiency do not change from one layer to the other.

A further advantageous effect in connection with the invention is due to the fact that the outlet for the rejects includes one or more compartments constricted at the ingress and egress end thereof, which makes it possible to reduce further the required back pressure. Such possibility is of special importance when the separator is equipped for feeding into the separator a flow of water or other liquid under pressure at the outlet or nozzle end for the heavy fraction. This flow of pressure liquid, which is additional to the tangential feed of the suspension into the separator generally near the discharge outlet thereof for the light fraction or accepts, is sometimes referred to hereinafter as "action water." Due to said constrictions it may be possible to reduce the quantity of action water as well as the pressure thereof to a minimum. Also the flow of rejects through the second outlet will be less responsive to or more independent of adjustments of the operational levels due to said constrictions.

It is a broad object of the invention to provide a novel and improved method of separating a suspension into a light fraction and a heavy fraction and also a novel and improved hydrocyclone separator unit for carrying out the method with which the separation of the suspension into a light fraction and a heavy fraction can be carried out with a high degree of efficiency and the danger of a clogging of the discharge outlet with the heavy fraction is virtually eliminated, or at least so greatly reduced that special flushing or rinsing means are required only under very unusual or exceptional operational conditions.

A more specific object of the invention is to provide a novel and improved method of separating a suspension into a light fraction and a heavy fraction and a novel and improved hydrocyclone separator unit for carrying out the method which permits the freedom within a wide range as to the selection of the pressure at which the separation is effected. This has the advantage that the separating operation can be readily integrated in other operational steps carried out under pressure by selecting pressures which are compatible for all operations involved. For instance, a pressure pump may be provided anterior of the hydrocyclone separator assemblage which imparts to the suspension to be separated a pressure such that both fractions, after being discharged from the separator assemblage, are forced through one or several subsequent treatment stations without requiring to be further kinetically energized.

Another specific object of the invention is to provide a novel and improved hydrocyclone separator unit of the general kind above referred to and provided with a plurality of stacked hydrocyclone separators disposed in several layers and comprising means for maintaining in said first and second receptacles when the hydrocyclone separator unit is in operation, an operational level of the light fraction and an operational level of the heavy fraction, respectively, which are of at least substantially the same height and above said second outlet of the hydrocyclone separators in the uppermost of said operational layers.

Another specific object of the invention is to provide a novel and improved hydrocyclone separator unit of the general kind above referred to in which each of the hydrocyclone separators comprises at least one duct tangentially connected with said elongated chamber for feeding suspension under pressure into the same and in which the cross sectional flow area of said duct is less than the cross sectional flow area of said second outlet at the mouth thereof. With this arrangement the danger of the second outlet being clogged is further decreased because any particles in the suspension which are great enough to cause a clogging of the second outlet are caught by the inlet opening, which is then possibly clogged. However, there may be a plurality of inlet ducts in every separator which means that the separator can be used until all inlet ducts have been clogged which may take a rather long period of time. Moreover, when all the inlets of a hydrocyclone separator of the unit are thus finally

clogged this cannot cause any damage because it only entails that one of the separators of the multiple separator unit is automatically shut off entirely so that no unseparated suspension can pass through said separator and if the pressure in the first receptacle is greater than the pressure in the second receptacle heavy fraction cannot pass from the second receptacle through the chamber of the said separator to the first receptacle and be mixed with separated light fraction. Since the unit usually comprises a great number of hydrocyclone separators the effect of one of the separators being shut off is of very little importance and only when a plurality of separators, for instance 10% or more, has been in this way shut off, it may be necessary to have these separators rinsed or flushed.

Still another specific object of the invention is to provide a novel and improved hydrocyclone separator unit of the general kind above referred to in which the vortical flow within the hydrocyclone separators and with it the percentage of the light fraction or accepts recovered from the suspension fed into the separators are markedly increased by feeding into the separator at the outlet or nozzle end thereof for the heavy fraction a flow of action water under pressure.

Other and further objects, features and advantages of the invention will be pointed out hereinafter and set forth in the appended claims constituting part of the application.

In the accompanying drawing several embodiments of the invention are shown by way of illustration and not by way of limitation.

In the drawing:

FIG. 1 shows diagrammatically an elevational view, partly in section, of a hydrocyclone separator unit according to the invention,

FIG. 2 is a sectional view taken on line II-II of FIG. 1,

FIG. 3 is an elevational view, partly in section, of a multiple hydrocyclone separator installation according to the invention,

FIG. 4 is a view taken on line IV-IV of FIG. 3, and

FIG. 5 is a sectional, enlarged detail view of the outlet or nozzle for the discharge of the heavy fraction as may be used in the separators according to FIGS. 1 and 3.

Referring first to FIGS. 1 and 2 in detail, these figures show a hydrocyclone separator unit including a number of stacked hydrocyclone separators disposed in five layers and with their geometric axes in horizontal orientation. Each layer comprises three separators 1 the axes of which are parallel. Each of the separators comprises an elongated generally conical chamber of circular cross section having at one end a first outlet 2 for the discharge of the light fraction or accepts into a first receptacle 3 and at the other end a second outlet or nozzle 4 for the discharge of the heavy fraction or rejects into a second receptacle 5. The suspension to be separated is fed under pressure from a feeding chamber or container 6 into the separators near the outlet 2 thereof through tangential ducts 7 as shown in FIG. 2. The second outlet 4 is by means of one or more tangential ducts 8 in communication with a separate chamber 9 which serves to supply action liquid, as previously defined, to the separator to increase the vortical action within the separator and particularly within the nozzle thereof. The suspension to be separated is fed to the chamber or container 6 through a flanged connection 10 and the light fraction and the heavy fraction are discharged from the receptacles 3 and 5 respectively through flanged connections 11 and 12 respectively, each provided with an adjustable valve 13 and 14 respectively. The receptacles 3 and 5 and the container 6 are closed at the top and the levels 15 and 16 in the receptacles 3 and 5 are maintained above the level of the second outlet 4 of the separator or separators in the uppermost layer in operation. The said levels may be at the same height as is shown. The height of the levels 15 and 16

is adjustable by means of the valves 13 and 14 respectively and the height of the level 17 in the container 6 may be adjusted by regulating the feed of the suspension through the flanged inlet connection 10. A conventional flow regulator included in connection 10 is diagrammatically indicated at 50. The level 17 is also maintained above the level of the outlet 4 and may be of the same height as the levels 15 and 16. The action water supply chamber 9 is preferably also closed at the top as shown in FIG. 1 and is provided with a flanged inlet connection 18. The level of the liquid in the chamber 9 must be above the level of the outlet 4 of the separators in the uppermost layer; the chamber may be kept wholly filled when in operation.

As shown in FIG. 1, the level 16 in the second receptacle 5 may be controlled by a measuring device 19, such as a pressure indicator, which, in any known manner, may be arranged to actuate the valve 14 by means of a motor 20 so that the level 16 is automatically kept at least substantially constant. In addition, suitable conventional time-control means 21 may be provided actuating the motor 20 to open the valve 14 periodically at predetermined intervals independent of any impulses from the controlling device 19. Due to the action of the time-control means 21 the level 16 in the receptacle 5 or the pressure external of the outlets 4 is periodically released whereby, if necessary, any accumulations in the nozzles 4 can be forced out through the nozzles due to a temporary increase in the difference of pressure within the nozzle and at the outside thereof. Such accumulations may form under exceptional operational conditions and cause clogging of the nozzles. The effect of the rinsing actions may be further increased by using nozzles made of elastic material such as rubber. The first receptacle 3 may also be provided with separate means such as pressure indicator 22 controlling a motor 23 for automatically controlling and adjusting the level 15 in receptacle 3 and conventional time-control means 24 may be provided replacing, or coacting with the time-control means 21 and acting upon the valve 13 for a temporary increase of the pressure inside the nozzle 4.

The receptacles 3 and 5 and the container 6 are shown as closed at the top and this may be of advantage because it will then be possible to use high pressures in the compartments 3, 5 and 6 and at the same time to have the levels 15, 16 and 17 only slightly above the uppermost layer of separators.

When starting the separating operation, the levels in the receptacles 3 and 5 are first adjusted, by means of the valves 13 and 14, to about the same height at the desired output. The valve 13 is then further adjusted so that the required separation efficiency is obtained. The levels may now be automatically maintained.

In FIG. 2 the minimum diameter d_1 of the outlet 4 for the heavy fraction of the mouth thereof is greater than the diameter for d_2 of each of the inlets 7 for the suspension. As is shown in FIG. 1, the diameter of the outlet 2 for the accepts at the mouth thereof within the chamber should also be greater than the diameter of the outlet 4 for the rejects. In this connection it should be pointed out that the inlet for the suspension need not be of circular cross section, but may also have any other suitable configuration, such as a rectangular cross section. It is only essential that the aforementioned ratio of the effective flow areas is maintained.

The correlation of the effective flow areas prevents the ingress of solid particles contained in the suspension into the hydrocyclone separator which are larger than the effect of entry of such large solid particles into the separator chamber will reduce the danger of clogging to a minimum.

FIGS. 3 and 4 show an installation comprising a plurality of stacked hydrocyclone separators 31. As it is shown in the figures, the separators are radially disposed in several layers in a common housing 32 such as de-

scribed for instance in copending U.S. patent application Ser. No. 137,809, filed Sept. 13, 1961.

The discharge nozzle 33 for the heavy fraction or rejects of each hydrocyclone discharges into a central, generally cylindrical chamber 34. As a result heavy fraction accumulates in chamber 34 and is maintained within the chamber at least at such a level that all the nozzles discharging into the chamber are submerged in the heavy fraction therein. Chamber 34 may be closed at the top.

The light fraction or accepts are discharged into a common annular space 35 through outlets 36. The suspension to be separated is fed through a duct 40 into an intermediate annular chamber 45 and enters the individual separators through tangentially disposed ducts 37. Action water is fed into the separators through a duct 38 and a second intermediate chamber 39 in the manner described in connection with FIG. 1.

The light fraction is discharged from chamber 35 through a duct 41 including valve 42 which is diagrammatically indicated as a manually operable valve. The heavy fraction is discharged from the central chamber 34 through a duct 43 including a valve 44 also diagrammatically shown as a manually operated valve. Either of the valves or both may be automatically operated and, if necessary, also time-controlled, as described in connection with ducts 11 and 12, to increase the pressure within the separator chambers or to reduce the pressure within chamber 34 preferably at time-controlled periodic intervals, thereby effecting flushing of the nozzles if necessary.

The pressure in chambers 34, 35 and 45 balance each other and may be easily adjusted to the desired values by means of valves 42 and 44. The pressure in the inlet 40 for the suspension may be maintained for instance at a pressure of 2.5 kg./cm.² above atmospheric pressure and the pressures in outlets 41 and 43 may be maintained at a pressure of 1.5 kg./cm.² and 1.3 kg./cm.² respectively.

The reject nozzles 4 or 33 may be of conventional design, but they may also have structures as shown in FIG. 5. According to this figure the nozzle is integral with the body 110 of the separator proper and includes one or several, preferably conical and serially aligned compartments or chambers 111 and 112. Both chambers are constricted at the ingress and egress end by inwardly protruding flanges or lips 113, 114 and 115 respectively. The lips are slightly tilted toward the mouth of the nozzle so that they gradually decrease the effective flow area in the direction of the flow. It has been found that the provisions of one or several chambers or compartments in the nozzle for discharge of the heavy fraction will increase the separation efficiency of the separator, even though the mouth of the nozzle is below the level of the heavy fraction in the container into which the nozzle discharges. Tests have shown that there is no danger that heavy fraction will be sucked back into the separator thereby adversely affecting separation efficiency.

Chambers 111 and 112 may be cylindrically shaped instead of being conical as shown.

For feeding action water into the nozzle tangentially disposed ports 116 and 117 are provided leading into the nozzle chamber 111 and 112 respectively.

The action water may be fed to ports 116 and 117 at a pressure of between 1.1-4.5 kg./cm.² absolute pressure, preferably 1.5-4.0. Generally speaking, the pressure of the action water should be approximately the same as that of the inlet for the suspension fed into the separator through ducts 7 and 37 respectively, but may be slightly less.

The anticlogging effect obtained by the flexible lips or flanges of FIG. 5 may also be obtained by making the nozzle of FIG. 5, or at least the tip end thereof of a radially expandible material such as rubber. The change in pressure effected in the time-controlled pressure-regulating means, as described in connection with ducts 11 and 12 in FIG. 1 will then cause a radial expansion of the flexible portion of the nozzle at predetermined time intervals as

controlled by time-control means 21 and 24 respectively, thereby flushing out any accumulations in the nozzles.

It has been found that the efficiency of separator assemblages of the kind as hereinbefore described can be markedly increased by correlating the free flow areas of the inlet for the suspension, the outlet for the heavy fraction and the outlet for the light fraction. Accordingly, in the separators according to FIGS. 3 and 4 the diameter of the first outlet 36 should also be greater than the diameter of the second outlet 33 and the last mentioned diameter should be greater than the diameter of each of the inlets 37 of the separators.

While the invention has been described in detail with respect to certain now preferred examples and embodiments of the invention, it will be understood by those skilled in the art after understanding the invention that various changes and modifications may be made without departing from the spirit and scope of the invention, and it is intended, therefore, to cover all such changes and modifications in the appended claims.

What is claimed as new and desired to be secured by Letters Patent is:

1. A method of separating a suspension into a light fraction and a heavy fraction in a hydrocyclone separator assemblage including a plurality of hydrocyclone separators disposed in several superimposed layers and with their geometric axes in an at least substantially horizontal orientation, each of said separators including an elongate chamber of circular cross-section having at one end a first outlet for the discharge of light fraction into a first receptacle common to all separators and at the other end a second outlet for the discharge of heavy fraction into a second receptacle also common to all separators, said assemblage further including conduits for discharging the light fraction and the heavy fraction from the first and the second receptacle respectively, and a common suspension supply container for feeding suspension in tangential direction into said chamber of the separators, said method comprising the steps of discharging under pressure the heavy fraction into said second receptacle when the separator assemblage is in operation, and controlling the discharge of the light fraction and the heavy fraction from said first and second receptacles respectively so as to maintain the operational levels of the light fraction and the heavy fraction respectively in said receptacles at least at substantially the same height and above said heavy fraction outlets of the hydrocyclone separators in the uppermost one of said layers.

2. A method according to claim 1 and further comprising the step of supplying suspension to said common supply container so that the operational level of suspension therein is of at least substantially the same height as the operational levels of the light and heavy fractions in said receptacles.

3. A method according to claim 1 and further comprising the step of maintaining the pressure in the first receptacle in excess of the pressure in the second receptacle.

4. A hydrocyclone separator assemblage for separating a suspension into a light fraction and a heavy fraction, said assemblage comprising, in combination:

a plurality of hydrocyclone separators each including an elongate chamber of circular cross-section having at one end a first outlet for the discharge of light fraction and at the other end a second outlet for the discharge of heavy fraction;

a first receptacle communicating with all the first outlets for receiving therein the discharge from all said first outlets;

a second receptacle communicating with all the second outlets for receiving therein the discharge from all said second outlets;

a third receptacle for receiving therein a supply of suspension;

a duct for each of said hydrocyclone separators tangentially connecting said third receptacle with the respective elongate separator chamber, the cross-

sectional flow area of each of said ducts being less than the cross-sectional flow area of the respective second outlet at the mouth thereof;

conduits connected to said first and second receptacles for discharging the light fraction and the heavy fraction, respectively, from the same; and

control means connected to each of said conduits for controlling the discharge flows therethrough so as to maintain, when the hydrocyclone separator assemblage is in operation, in said first and second receptacles operational levels of the light fraction and the heavy fraction, respectively, of at least substantially the same height and above the level of the second outlet of each of the hydrocyclone separators.

5. A hydrocyclone separator assemblage for separating a suspension into a light fraction and a heavy fraction, said assemblage comprising, in combination:

a plurality of stacked hydrocyclone separators disposed in several layers and with their geometric axes in at least substantially horizontal orientation, each of said separators including an elongate chamber of circular cross-section having at one end a first outlet for the discharge of light fraction and at the other end a second outlet for the discharge of heavy fraction;

a first receptacle communicating with all the first outlets for receiving the discharge from all said first outlets;

a second receptacle communicating with all the second outlets for receiving the discharge from all the second outlets;

a conduit for discharging the light fraction and a conduit for discharging the heavy fraction from said receptacles;

control means connected to each of said conduits to control the discharge flows through said conduits to maintain, when the assemblage is in operation, in said first and second receptacles operational levels of the light fraction and the heavy fraction, respectively, which are of at least substantially the same height and above the level of the second outlets of the hydrocyclone separators in the uppermost layer; a third receptacle for receiving therein a supply of suspension;

means for feeding suspension into the third receptacle, first conduit means tangentially connecting said third receptacle with the chamber of each of said separators for feeding tangentially directed suspension under pressure into said chambers to generate a vortical action in the respective chamber and second outlet;

a second conduit means for feeding suspension to the third receptacle, said second conduit means including means for regulating the flow of suspension therethrough to maintain the operational level of the suspension in said third receptacle above the level of the second outlet of the separators in the uppermost layer of the assemblage.

6. A hydrocyclone separator assemblage according to claim 5 in which said first conduit means comprises a duct for each of the hydrocyclone separators, each of said ducts leading tangentially into the respective elongate chamber, the cross-sectional flow area of each of said ducts being less than the cross-sectional flow area of the respective second outlet at the mouth thereof.

7. A hydrocyclone separator assemblage according to claim 5 in which the cross-sectional flow area of each of said second outlets is smaller than the cross-sectional flow area of the respective first outlet at the mouth thereof within the elongate chamber of the respective separator.

8. A hydrocyclone separator assemblage according to claim 5 wherein the second outlet of each separator includes a compartment constricted at the ingress and egress end thereof.

9. A hydrocyclone separator assemblage according to claim 5 wherein the second outlet of each separator includes at least two lengthwise aligned compartments, each being constricted at the ingress and egress end thereof.

10. A hydrocyclone separator assemblage according to claim 5 wherein the second outlet of each of said separators includes a compartment constricted at the ingress and egress end thereof, a supply container common to all separators for receiving a supply of action liquid, conduit means connected to said container for maintaining therein a liquid level above the level of the second outlet of the separators in the uppermost layer, and conduit means tangentially connecting said container to each of said constricted compartments for feeding action liquid under pressure into said compartments to increase the 15 operational vortical action therein.

11. A hydrocyclone separator assemblage according to claim 5 wherein the second outlet of each of said separators includes several lengthwise aligned compartments each being constricted at the ingress and egress end thereof, and a supply container common to all separators for receiving therein a supply of action liquid, conduit means connected to said container for maintaining therein a liquid level above the level of the second outlet of the separators in the uppermost layer, and conduit means 25 tangentially connected to at least one compartment of each of said second outlets for feeding action liquid under pressure into said compartments to increase the operational vortical action in said second outlets.

12. A hydrocyclone separator assemblage according to claim 5 wherein said control means for maintaining said operational levels of the light fraction and the heavy 30

fraction comprise a light-fraction regulating device connected to the discharge conduit of said first receptacle and a heavy-fraction regulating device connected to the discharge conduit of said second receptacle for regulating the outflow of the light fraction and the heavy fraction respectively with reference to each other.

13. A hydrocyclone separator assemblage according to claim 12 and comprising time-controlled means connected to at least one of said light fraction and heavy fraction regulating devices for temporarily reducing the pressure external of said second outlets at predetermined intervals.

14. A hydrocyclone separator assemblage according to claim 12 wherein said control means for maintaining said operational levels of the light fraction and the heavy fraction comprise level controlling devices controlling at least one of said levels and actuating at least one of said regulating devices for maintaining said operational levels.

[57] ABSTRACT

Horizontally oriented hydrocyclones disposed in superimposed layers are arranged to discharge light fractions into a common compartment and heavy fractions into another common compartment. A third compartment is arranged common to all feed inlets. Conduits and regulating devices maintain the operational levels in the compartments above the heavy fraction outlets in the uppermost layer.

[57] **ABSTRACT**

Horizontally oriented hydrocyclones disposed in superimposed layers are arranged to discharge light fractions into a common compartment and heavy fractions into another common compartment. A third compartment is arranged common to all feed inlets. Conduits and regulating devices maintain the operational levels in the compartments above the heavy fraction outlets in the uppermost layer.

**REEXAMINATION CERTIFICATE
ISSUED UNDER 35 U.S.C. 307****NO AMENDMENTS HAVE BEEN MADE TO
THE PATENT**AS A RESULT OF REEXAMINATION, IT HAS
BEEN DETERMINED THAT:

5 The patentability of claims 1-14 is confirmed.
